UNITED STATES PATENT OFFICE

135,887

DESIGN FOR A FLEXIBLE SLAT BEDSPRING

Maxon H. Pulford, Duluth, Minn., assignor to
De Witt-Seitz Company, Duluth, Minn., a cor-
poration of Maine

Application November 24, 1942, Serial No. 108,862

Term of patent 3½ years

To all whom it may concern:

Be it known that I, Maxon H. Pulford, a citizen of the United States, residing at Duluth, in the county of Saint Louis and State of Minnesota, have invented a new, original, and ornamental Design for a Flexible Slat Bedspring, of which the following is a specification, reference being had to the accompanying drawing, forming part thereof.

Figure 1 is a top plan view of the flexible slat bedspring, showing my design; and

Figure 2 is a side elevational view thereof.
Figure 3 is an enlarged fragmentary detail perspective view of one corner of the bedspring.

Figure 4 is an enlarged fragmentary detail perspective view of one slat in the end frame bar portion of the bedspring.

I claim:

The ornamental design for a flexible slat bedspring, as shown.

MAXON H. PULFORD.
